UNITED STATES PATENT OFFICE.

BENJAMIN SHERWOOD AND DANIEL FITZGERALD, OF NEW YORK, N. Y.

IMPROVEMENT IN SAFES.

Specification forming part of Letters Patent No. 62,974, dated March 19, 1867; antedated March 12, 1867.

To all whom it may concern:

Be it known that we, BENJAMIN SHERWOOD and DANIEL FITZGERALD, of the State, city, and county of New York, have invented certain new and useful Improvements in Fire and Burglar Proof Safes; and we do hereby declare that the following is a full, clear, and exact description of the same, reference being had to the accompanying drawing, which forms part of this specification, in which—

Figure 1 is a general perspective view. Fig. 2 shows the safe proper detached. Fig. 3 is a vertical section of our improved fire and burglar proof casket.

The first part of our invention consists in a spherical burglar-proof casket.

The second part of our invention consists in arranging such casket within a safe or other receptacle, which is otherwise filled by a removable book-case.

The third consists in constructing the safe with the opening of access on the side thereof, in combination with a book-case inserted therein, and arranged so as to be readily withdrawn horizontally.

The fourth consists in combining, with the safe or receptacle for books and the book-case, a competent support for the book-case when withdrawn from the safe.

To enable others to make and use our invention, we will proceed to describe the same, referring to the drawing annexed.

A represents a safe constructed, as regards frame and filling, in any usual manner. Instead, however, of sitting low on short legs, it is elevated some two feet from the floor; and instead of having the opening for access in the front, as customary, we make the opening at the side, as seen at B in Figs. 1 and 2. At the remotest side from that of the opening of access we place our improved burglar-proof casket, the construction of which is peculiar. A sectional view is given in Fig. 3, showing that it is composed of two separate shells. The inner shell is made in two half-spherical sections of chilled iron, which, being cast separately, are then placed together; and the outer shell is formed by running molten iron (Franklinite is best) around it. In forming this outer shell we chill the outer surface thereof by the use of a cast-iron mold, or other means common to the art of iron-founding. The casket

thus made, being a hollow sphere formed inside and out of chilled iron, constitutes a receptacle for valuables, which, in consequence of the combined chilled iron and spherical form, it is impossible to enter by any drill, sledge, or other instrument ordinarily employed for the purpose. In lieu of the true sphere an oval and similar forms may be used; but the spherical is preferable.

The opening of access to the casket is circular, and is closed by a plug, C, turned and fitted snugly therein, and this plug is made impervious to the drill. The drawing, Fig. 3, shows the plug in longitudinal section, exhibiting a step, 1, corresponding to a rabbet, 2, in the circular opening. The plug is secured in its place by a suitable lock. The spherical shape of the casket forms a saucer in the bottom of the lower section thereof, and into this we place a small quantity of alum, 4, which will melt in case of fire and produce moisture, thus preventing combustion.

For further protection, the casket is fixed permanently within the safe aforesaid, at the remotest point from the opening of access to the safe, as before mentioned; and, instead of using a simple door to close the opening, we construct a book-case, D, sufficiently large to fill the entire space within the safe, except that occupied by the casket, and then the ordinary doors B are closed against this book-case, as usual.

In order to unlock and enter the casket, when the same is permanently placed as above, we provide a small circular opening, E, in the safe A, near the location of the casket, and have the mouth of the casket placed opposite said circular opening in the safe.

In order that the book-case may be easily removed from the safe, for access to the books or other contents of such case, we arrange said case to slide in and out of the safe horizontally. Fig. 1 shows the book-case partially withdrawn. The case is provided with rollers, if necessary, to reduce friction. For the support of the book-case, when withdrawn from the safe, we construct a platform, F, immediately adjacent thereto. The book-case is run out on this platform, where it remains, if required, while the books are in use.

For further convenience, we have constructed a desk, G, right in front of the platform F,

and this desk is also extended along in front of the safe A, and covers it more or less with cabinet-work for concealment, thus giving the whole the semblance of an office fixture. For these purposes, and also to announce to one at the desk the approach of any person to the safe, we have arranged a mirror, H, in front of the safe over the desk.

As shown in the drawing, the mirror is at one side, exposing the access to the casket; but, of course, we are not confined to any particular size.

J J J is a railing, constructed so as to be turned up out of the way over the desk, or used on either side thereof. It is pivoted to the desk at K, and, in the corresponding place, at the opposite side. Said railing has a balance-weight, L, fixed to it, so as to facilitate handling when it is desired to raise it up or reverse it.

Having thus described our invention, what we claim as new, and desire to secure by Letters Patent, is—

1. The spherical fire and burglar proof casket, constructed substantially as specified.

2. Arranging the said casket within a safe or other receptacle, as set forth, which is otherwise filled by a book-case or its equivalent, as described.

3. Constructing the safe with the opening of access on the side thereof, in combination with a book-case inserted therein, and arranged so as to be readily withdrawn therefrom horizontally, all substantially as described.

4. Combining with the safe and the book-case, as above, the platform F, or equivalent support for the book-case, when withdrawn from the safe, as aforesaid.

BENJAMIN SHERWOOD.
DANIEL FITZGERALD.
